CLAIM

The ornamental design for a wall mounting hose reel, as shown and described.

DESCRIPTION

FIG. 1 is a top left perspective view of the wall mounting hose reel of the present invention;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a top right perspective view thereof.

The broken lines adjacent the solid lines represent unclaimed boundaries of the claim and the other broken lines represent unclaimed portions of the claimed design.
